FIG. 1 is an exploded, front-left side perspective of a self-mating extrusion assembly for LED-based lighting apparatus thereof;

FIG. 2 is back-left side perspective view thereof;

FIG. 3 is a right side elevation view of the assembly shown in FIG. 1; the left side elevation view being a mirror image thereof;

FIG. 4 is front side elevation view; the back side elevation view being a mirror image thereof;

FIG. 5 is a top side elevation view thereof; and,

FIG. 6 is a bottom side elevation view thereof.

The broken break lines and brackets in the drawings indicates that the appearance of any portion of the self-mating extrusion assembly for LED-based lighting apparatus between the break lines forms no part of the claimed design.
